Primary Examiner — Cynthia Ramirez(74) *Attorney, Agent, or Firm* — William H. Dippert;
Laurence A. Greenberg; Werner H. Stemmer(57) **CLAIM**

The ornamental design for a desktop waste bin, as shown and described.

DESCRIPTION

FIG. 1 is a perspective view of a desktop waste bin, showing my new design.

FIG. 2 is a top plan view thereof.

FIG. 3 is a front elevation view thereof.

FIG. 4 is a right-side elevation view thereof.

FIG. 5 is a rear elevation view thereof.

FIG. 6 is a bottom plan view thereof; and,

FIG. 7 is a left-side elevation view thereof.

The broken lines in the drawings show portions of the desktop waste bin which form no part of the claimed design.
